UNITED STATES PATENT OFFICE.

ANTONIO COLUCCI, OF BROOKLYN, NEW YORK.

DESIGN FOR A LAMP STAND.

Application filed July 28, 1928. Serial No. 27,611. Term of patent 14 years.

To all whom it may concern:

Be it known that I, ANTONIO COLUCCI, a citizen of the United States, residing in the borough of Brooklyn, county of Kings, city and State of New York, have invented a new, original, and ornamental Design for a Lamp Stand, of which the following is a specification, reference being had to the accompanying drawing, forming a part thereof.

The drawing shows a perspective view of my design.

I claim:

The ornamental design for a lamp stand substantially as shown.

ANTONIO COLUCCI.
